CLUTCH MECHANISM FOR SEWING MACHINES

Edgar Schoij, Chicago, Ill., assignor to Union Special Machine Company, Chicago, Ill., a corporation of Illinois

Application October 1, 1946, Serial No. 700,480

7 Claims. (Cl. 74—144)

1

The invention relates to new and useful improvements in a clutch mechanism of the barrel type for imparting intermittent movements to the feeding mechanism of a sewing machine.

An object of the invention is to provide an intermittently operating clutch mechanism of the above type wherein the gripping surface of the clutch barrel is eccentric to its axis of rotation so that the gripping line between the roller and the clutch block shifts back and forth on the clutch block for each rotation of the shaft and wherein the gripping face of the clutch block is so shaped that the wedge angle between the clutch barrel and the clutch block remains substantially constant as the gripping lines shift.

A further object of the invention is to provide a clutch mechanism of the above type wherein means is provided for changing the eccentricity of the clutch barrel so that the area over which the grip shifts may be increased or decreased to further distribute the wear and increase the life and efficiency of the clutch.

These and other objects will in part be obvious and will in part be hereinafter more fully stated.

In the drawings which show the invention as applied to a cup feed type of sewing machine,

Figure 1 is a view partly in side elevation with parts broken away to show some of the inner mechanism and with parts in vertical section,

Figure 2 is a vertical sectional view through a portion of the machine and showing the means whereby access may be had to the clutch mechanism for varying the eccentricity of the setting of the clutch barrel on the actuated feed shaft,

Figure 3 is a front view of a portion of the housing for the clutch mechanism showing the cap screw removed from the opening and the indicia on the clutch barrel for indicating the relative amount of eccentricity,

Figure 4 is an enlarged sectional view through the clutch mechanism, the section being taken on line 4—4 of Figure 1,

Figure 5 is a section on line 5—5 of Figure 4,

Figure 6 is a sectional view taken on the line 6—6 of Figure 4,

Figure 7 is a sectional view taken on the line 7—7 of Figure 4,

Figure 8 is a sectional view on the line 8—8 of Figure 4,

Figure 9 is a diagrammatic view showing the inner surface of the clutch barrel, the clutch block and one of the clutch rollers and the shifting of the gripping line of the roller on the clutch block during the rotation of the eccentrically set clutch barrel and also showing that the wedge angle

angle between the inner surface of the clutch barrel and the gripping surface of the clutch block is substantially equal for each increment of rotation of the clutch barrel,

Figure 10 is a diagrammatic view showing the shifting of the setting of the clutch barrel from zero where the inner surface of the clutch barrel is concentric to the axis of the actuated shaft to maximum eccentricity of the clutch barrel relative to the axis of said shaft.

While the clutch mechanism embodying the improvements may be used for many purposes, it is particularly designed for use in connection with the feeding mechanism of a sewing machine wherein the fabric is advanced to the stitching mechanism by an intermittently rotated part.

The machine illustrated in the drawings is a cup feed machine of the type shown in the patent granted Edgar Schoij October 10, 1944, No. 2,360,075.

Briefly, the machine includes a housing or frame 1 in which is mounted the main actuating shaft 2. Said housing is provided with an overhanging portion 3 supporting an inner feed cup 4 and an outer feed cup 5 between

which the fabric sections are gripped and fed through the stitching mechanism. The stitching mechanism includes a needle 6 which is carried by a needle bar reciprocated by suitable mechanism from the main shaft 2.

Cooperating with the needle 6 is a thread carrying looper 7 which moves into the needle thread loop at one side of the fabric and then positions itself at the other side of the fabric. The looper is carried by a supporting bar which is actuated by suitable mechanism from the main shaft 2.

Cooperating with the looper 7 is a loop carrier or spreader 8 which engages the looper thread loop and positions it for the needle to enter prior to penetrating the fabric sections. This spreader 8 is carried by a spreader bar which is actuated by suitable mechanism from the main shaft 2.

The feed cup 4 is carried by a shaft 9 mounted for rotation in a sleeve 10 which in turn is fixed to the frame of the machine. The feed cup 5 is carried by a shaft 11 which is connected through

a universal joint with a shaft 12 mounted in a suitable bearing in the overhanging arm 3. At the upper end of the shaft 9 there is a gear wheel 13 carried by a hub 14 which is secured to a flat section 15 on the actuated shaft by means of a set screw 16. The gear 13 meshes with a gear 17 on the shaft 12 and thus rotations imparted to the shaft 9 are also imparted to the shaft 11; thereby the feed cups are operated in unison and turned increment by increment for feeding the

fabric to the stitching mechanism. The purpose of the universal connections between the shafts 11 and 12 is to permit the feed cups to be separated for the insertion or removal of the material to be stitched.

The improvement has to do with the clutch mechanism for imparting feeding movements to the shaft 9. The clutch mechanism includes two parts, one of which is the actuating part for turning the shaft 9, and the other is the holding or braking clutch for holding the shaft when turned to a set position and preventing retrograded movements thereof as the actuating clutch is returned for a new grip. These two parts are similar in construction and a detailed description of one will answer for the other. The clutch mechanism includes a sleeve 18 to which the clutch barrel 19 of the actuating clutch part is integrally connected. The clutch barrel 20 of the braking clutch is also integrally connected with this sleeve. On the actuating shaft 9 is a hub 21 which is cylindrical but eccentrically set relative to the axis or center of the shaft 9. This hub is provided with a flat portion 22 and the sleeve 18 is secured to this flat portion by a set screw 23. As shown in Figure 8, there are three set screws, one of which is indicated at 23, another at 24, and another at 25. By loosening the set screws, the sleeve may be adjusted on this eccentric hub so as to position any one of the three set screws directly over the flat section. This is for the purpose of changing the eccentric setting of the clutch barrels on the shaft 9, as will be more fully explained hereinafter.

Mounted for free rotation on the shaft 9 is a clutch plate 25^a. This clutch plate carries on its under face a clutch block 26. The clutch block 26 is rigidly secured to the clutch plate by suitable screws 27. The clutch barrel 19 projects upwardly from the sleeve 18 and the clutch block extends downwardly from the clutch plate 25^a and the outer face of the clutch block is opposed to the inner face of the clutch barrel. The clutch block has three wedging faces which are all similar in shape and are numbered 28. Disposed between each operating face of the clutch block and the inner surface 29 of the clutch barrel 19 is a roller 30. The operating surfaces of the clutch block 28 are eccentric to the inner surface of the clutch barrel and the rollers are so dimensioned that they will be frictionally gripped by the clutch block and pressed into frictional gripping engagement with the inner face of the clutch barrel when the clutch block is oscillated in a clockwise direction as viewed in Figure 6. Associated with each roller is a spring 31 mounted on a projecting lug rigidly supported by a post 32, which in turn is rigidly attached to the clutch plate 25^a. These springs are under compression and constantly force the roller in a counter-clockwise direction so as to hold the rollers in contact with the clutch block and the clutch barrel.

The clutch plate 25^a has a projecting arm 33 carrying a ball stud 34 to which a link 35 is connected. This link 35 is connected at its other end to a slotted arm 36 mounted on a shaft 37. The shaft carries an arm 38 to which is connected an eccentric strap 39 cooperating with an eccentric 40 on the main shaft 2; as the main shaft rotates this eccentric will through the train of mechanism just described impart oscillations to the clutch plate and thus the clutch block moves first in one direction and then the other, gripping the rollers to move the clutch barrel when

moved in a clockwise direction and releasing the rollers so that the clutch block can be returned by a counter-clockwise movement to obtain a new clutch grip on the clutch barrel.

The clutching mechanism which serves to hold the shaft 19 in a set position is similar to the clutch mechanism for actuating the shaft except that the clutch block 41 is fixed to the sleeve 10 which in turn is fixed to the frame and held from movement. This clutch block 41 has the similarly shaped clutching faces 42 which engage rollers 43 and force the same into gripping contact with the clutch barrel 20. The clutch barrel will be turned by the actuating clutch block 18 through a given increment of movement and, when the actuating clutch block is turned in the opposite direction for a new gripping connection with the barrel 19, this barrel 20 will wedge the roller against the stationary clutch block 41 and prevent any turning of the shaft 9 in a reverse direction. Associated with the rollers 43 are compression springs 44 mounted on studs carried by posts 45 which are rigidly attached to the sleeve 10 and therefore these posts and springs are stationary the same as the clutch block 41.

The clutch plate 25^a is provided with an annular groove or channel 46 in the upper face thereof. Oil may be supplied to this channel through openings 47 in the gear 13. There are oil holes 48 through the clutch plate 25^a which are disposed between the posts 32 and the rollers for reciprocating the clutch.

In the operation of the actuating clutch, the roller is gripped between the clutch block and the inner surface 29 of the clutch barrel. If the gripping line of the roller with the clutch block were always in the same position, the clutch block would wear rapidly, forming a pocket which would soon permit the clutch to slip. One of the purposes of the invention is to provide a construction wherein the line of grip between the roller and the clutch block shifts for each increment of movement of the clutch barrel. This shifting of the gripping line of the clutch roller with the clutch block is accomplished by the eccentric setting of the clutch barrel.

As has already been noted, the outer surface of the hub 21 is eccentric to the center of the shaft. The center of the inner surface of the clutch barrel is also eccentric to the center of the hub.

Referring to Figure 10, the circle indicated at X is the circumference of the shaft and the center of the shaft is indicated at cs. The circle Z indicates the circumference of the hub and the center of the hub as shown in this view it at ch. The center of the inner surface of the clutch barrel, which is not indicated in this view, is shown at cb. When the centers cs, ch and cb are in alignment, then the clutch barrel is at its maximum eccentricity. In the preferred setting of these centers, the distance from the center of the shaft to the center of the hub is .005 inch and the distance from the center of the hub to the center of the barrel is .005 inch so that when the centers are in the position shown in this diagram, the eccentricity of the barrel is .010 inch from the center of the shaft. The set screw 25 is shown on this diagram and indicates the setting of the clutch barrel on the hub when the flat on the hub has been brought opposite the set screw 25. At this setting, the eccentricity of the clutch barrel is as noted .010 inch. By loosening the set screw 25, the clutch barrel can be shifted on the hub so as to bring the set screw 24 opposite the flat. This angle of shift is about 90 degrees and

when the set screw 24 is turned up against the flat so that the barrel, hub and shaft all turn as one unit, then the eccentricity of the clutch barrel is .007 inch. Again by loosening the screw 24 the barrel can be shifted about the hub until the flat is brought opposite the set screw 23. This shifting is through an angle of about 130° and when the set screw 23 is set up against the flat, then the eccentricity of the clutch barrel is .004 inch. The center of the clutch barrel as it is shifted about the hub moves in the circle indicated at Y and at one time it passes through the center of the shaft so that the eccentricity of the clutch barrel then is zero. In other words, the clutch barrel is concentric to the center of the shaft.

The set screws may be accessible by removing the cap plate of the machine, but preferably the housing has an opening 49 at the front thereof. Opposite the set screw 23 is an indexing numeral 4 (see Fig. 3) and this indicates that when the flat on the hub is opposite the set screw 23, the eccentricity of the clutch barrel is .004 inch. A like indexing numeral 1 is applied to the outer face of the clutch barrel opposite the set screw 24 (see Fig. 2) and a numeral 10 applied to the clutch barrel opposite the screw 25 (not shown). Assuming that the screw 23 engages a flat on the hub and it is desired to shift so as to increase the eccentricity to .007 inch, the set screw 23 is loosened, after which the feed cup is held by hand from turning and the hand wheel of the machine is rotated, which will turn the clutch barrel on the hub and when the set screw 24 is opposite the opening it will be opposite the flat because a holding of the feed cup prevents the flat from shifting. The set screw 24 is then tightened. The other set screw may also be tightened against the hub to aid in holding the clutch drum in a set position on the hub. In like manner, the eccentricity may be further adjusted by shifting the clutch drum to bring the set screw 25 opposite the flat. It is noted that the flat 15 at the upper end of the shaft, the flat 22 on the hub, and the flat 4^a which is contacted with by a set screw 4^b to lock the feed cup to the shaft are all in alignment. This greatly facilitates the assembling of the parts.

There is shown diagrammatically in Figure 9 the inner surface of the clutch barrel, a clutch block and one of the rollers. The clutch barrel is set eccentrically to the center of the shaft and therefore the center of the clutch barrel will move in the circular path cb. In this view, the position of the gripping surface of the clutch barrel when the maximum eccentricity is at the upper side of the figure is indicated by the circle 29^a. The gripping surface of the clutch barrel when the eccentricity is down is indicated at 29^b. The position of the roller when the eccentricity is up is indicated at 30^a and it will grip the surface 29^a of the clutch barrel at S and the clutch block at A. When the eccentricity is down, then the roller shifts to the position 30^b so that it grips the clutch barrel surface 29^b at S' and the clutch block at A'. It is noted that the line of grip of the roller and the clutch block shifts from A to A' during the rotation of the clutch barrel through 180 degrees and through the next rotation of 180 degrees the line of grip will shift back from A' to A. This shifting of the line of grip distributes the wear on the clutch block.

It will be noted that the surface of the clutch block 28 is curved and the purpose of this curving of the surface is to provide a substantially con-

stant wedge angle for all positions in which the roller is gripped by the clutch block. The wedge angle is the angle between a line tangent to the roller at the point of contact S between the roller and the clutch barrel and a line tangent to the roller at the point of contact A of the roller with the curved surface 28. A wedge angle is selected with the clutch barrel at maximum eccentricity and the roller at the position 30^a, 10 which wedge angle will prevent slippage, and the curvature of the clutch block face is so shaped that the wedge angles for each gripping position of the roller as it shifts back and forth on the face of the clutch block will be substantially equal regardless of where the gripping of the roller by the clutch block occurs. The center of the curved surface 28 is determined by dropping a line from the center O of the roller through the point of contact A, and where this line intersects a line drawn at right angles thereto and passing through the center C of the shaft determines the center of the curved surface of the block. This center is indicated at D. The angle between O—D and O—C equals the wedge angle for the roller in the position 30^a and likewise the angle between O'—D and O'—C equals the wedge angle for the roller at the position 30^b. These wedge angles are substantially equal and likewise the wedge angles for all gripping points 30 are substantially equal. With this shifting of the gripping line back and forth for each rotation of the clutch barrel and with the wedge angles substantially equal at all portions of grip, the life of the clutch is greatly increased 35 before the wear on the clutch block will be sufficient so as to change any of the wedge angles to produce slipping.

The machine is equipped as above noted with means whereby the eccentric setting of the clutch 40 barrel may be varied by loosening the screws securing the clutch barrel to the hub and shifting the same on the eccentric hub. The machine is preferably adjusted at the factory so that the screw 23 is in contact with the flat and this provides for an eccentricity of .004 inch. When the machine has been operated for some time and wear occurs, then the set screw 23 is loosened and the clutch barrel shifted until the screw 24 is opposite the flat. This increases the eccentricity 45 of the setting of the clutch barrel and it will also increase the distance between A and A', the limits of the area where the roller grips the clutch block, and bring new surfaces into contact with the roller. Then again, when wear is apparent, the set screw 24 can be loosened and the screw 25 brought opposite the flat and this will increase the eccentricity of .010 inch and it will also further increase the distance from A to A' over which the line of contact between the roller and the clutch block shifts. By these three settings, the area of the line of contact is increased from the original setting and thus the wear and life of the clutch are prolonged. Regardless of the eccentricity of the clutch barrel, 55 the wedge angles for all settings will be substantially constant. This not only permits a greater range of adjustment of the eccentricity, but it also prolongs the life of the clutch before wear can possibly change the wedge angle sufficiently to bring about slippage.

Let us assume that the machine is set for producing ten stitches to the inch and that the inner circumference of the clutch barrel is five inches. Then for each rotation of the clutch 75 barrel there would be fifty increments of move-

ment of the clutch barrel. While moving the clutch barrel through 180 degrees there would be twenty-five increments of movement. Let us assume that the distance from A—A' is at a maximum because of the setting of the clutch barrel at a maximum eccentricity. Each increment of movement along this line A—A' would be $\frac{1}{25}$ the distance. If the eccentricity of the clutch barrel is shifted so as to shorten the line A—A' still the increments of movement would be $\frac{1}{25}$ of whatever the distance is and therefore the distance between the lines of contact for one setting will be different than the distance between the lines of contact for another setting of the eccentricity of the clutch barrel. This further aids in the distribution of the wear on the surface from A—A'.

This construction of clutch wherein the wedge angle is maintained substantially constant for all points of grip accomplishes two distinct advantages in the operation of an eccentrically set clutch barrel. One, it enables the wedge angle to be selected which will give a long life to the clutch before the wear on the clutching face of the clutch block will be sufficient to produce slippage and in the second place, it permits a wide range of eccentric setting of the clutch barrel which results in a wide distribution of the wear on the clutch block, as the greater the eccentricity of the clutch barrel, the greater will be the area of the clutch block which is gripped by the clutch roller. This increased distribution of the gripping of the clutch block also greatly prolongs the life of the clutch. Furthermore in this constant wedge angle clutch all three rollers may have the same wedge angle and therefore each roller will carry about the same amount of load which reduces the wear rate.

Instead of the rollers, balls might be used. It is preferred, however, to use rollers, as the contact between the rollers and the parts directly associated therewith is a line contact instead of a point contact. While the clutch has been described in detail in connection with a feed cup type of machine, it will now be understood that the clutch may be used for imparting intermittent movement to a rotary part in other types of feeding mechanisms and also in other types of machines.

It will also be obvious that minor changes in the details of construction may be made without departing from the spirit of the invention as set forth in the appended claims.

I claim:

1. A clutch mechanism for sewing machines comprising an actuated shaft, a clutch barrel on said shaft, a clutch block associated with said barrel, gripping rollers between the clutch block and said barrel, means for oscillating the clutch block for moving said barrel intermittently, and means for securing said clutch barrel to said shaft with the clutching surface of the clutch barrel eccentric to the center of the shaft whereby the line of grip between the rollers and the clutching surfaces of the clutch block will shift as the barrel is rotated, the clutching surfaces of said clutch block being curved so that the wedge angle is substantially constant for all gripping positions of the rollers.

2. A clutch mechanism for sewing machines comprising an actuated shaft, a hub on said shaft, the center of which is eccentric to the shaft, a sleeve mounted on said hub, a clutch barrel on said sleeve, said clutch barrel being eccentric to the center of the hub, a clutch block

having a plurality of clutching surfaces, a gripping roller associated with each clutching surface of the clutch block and adapted to engage the clutch barrel, a compression spring associated with each roller for holding the same in engagement with the clutching surfaces of the clutch barrel and the clutch block, means for oscillating the clutch block for moving the barrel intermittently, each clutching surface of the clutch block being curved so that the wedge angle is substantially constant for all gripping positions of the rollers.

3. A clutch mechanism for sewing machines comprising an actuated shaft, a hub on said shaft, the center of which is eccentric to the center of the shaft, a sleeve on said hub, a driving clutch barrel and a braking clutch barrel carried by said sleeve, the clutching surface of each barrel being eccentric to the center of the hub, a clutch block associated with each barrel, means for holding one of said clutch blocks stationary, and means for actuating the other clutch block, rollers associated with each clutch block for gripping the clutch barrels, and a compression spring associated with each roller and normally tending to hold the roller in clutching engagement with the clutch blocks and clutch barrels, the clutching faces of each clutch block being curved so that the wedge angle is substantially constant for all positions of the rollers.

4. A clutch mechanism for sewing machines comprising an actuated shaft, a hub on said shaft, the center of which is eccentric to the center of the shaft, a sleeve on said hub, a driving clutch barrel and a braking clutch barrel carried by said sleeve, the clutching surface of each barrel being eccentric to the center of the hub, a clutch block associated with each barrel, means for holding one of said clutch blocks stationary and means for actuating the other clutch block, rollers associated with each clutch block for gripping the clutch barrels, a compression spring associated with each roller and normally tending to hold the roller in clutching engagement with the clutch blocks and clutch barrels, and means whereby said sleeve and clutch barrels may be shifted on said hub to different set positions for varying the eccentricity of the clutch barrel relative to the center of the shaft, the clutching surfaces of the clutch blocks being curved so that the wedge angle is substantially constant for all gripping positions of the rollers.

5. A clutch mechanism for sewing machines comprising an actuated shaft, a hub on said shaft, the center of which is eccentric to the center of the shaft, a clutch barrel mounted on said hub, the center of the clutch barrel being eccentric to the center of the hub, a clutch block associated with said barrel, gripping rollers between the clutch block and said barrel, means for oscillating the clutch block for moving the barrel intermittently, and means whereby said clutch barrel may be shifted on said hub to different set positions for varying the eccentricity of the clutch barrel relative to the center of the shaft.

6. A clutch mechanism for sewing machines comprising an actuated shaft, a hub on said shaft, the center of which is eccentric to the center of the shaft, said hub having a flat on one side thereof, a sleeve mounted on said hub, a clutch barrel carried by said sleeve, the center of the clutch barrel being eccentric to the center of the hub, a clutch block associated with said barrel, gripping rollers between the clutch block and said barrel, means for oscillating the clutch block

for moving said barrel intermittently, said sleeve having set screws extending therethrough at different radial points whereby a selected set screw may be positioned in radial alignment with the flat for securing the sleeve to the hub and by shifting from one set screw to another the eccentricity of the clutch barrel may be varied, and means associated with each set screw for indicating the eccentric setting of the clutch barrel.

7. A clutch mechanism for sewing machines comprising an actuated shaft, a hub on said shaft, the center of which is eccentric to the center of the shaft, a clutch barrel mounted on said hub, the center of the clutch barrel being eccentric to the center of the hub, a clutch block associated with said barrel, gripping rollers between the clutch block and said barrel, the clutching faces of each clutch block being curved so that the wedge angle is substantially constant for all positions of the rollers, means for oscillating the clutch block for moving the barrel intermittently,

and means whereby said clutch barrel may be shifted on said hub to different set positions for varying the eccentricity of the clutch barrel relative to the center of the shaft.
